ISAAC D. LOOKINGLAND, OF CHICAGO, ILLINOIS

SYSTEM AND MEANS FOR FEEDING WATER TO STEAM BOILERS

Application filed October 6, 1927. Serial No. 224,351.

My invention relates to improvements in methods and means for feeding water into steam boilers.

The object is to provide a system of boiler feed which shall be more economical than those now generally in use; which shall be automatic in its operation; which shall be capable of being operated manually if for any reason it does not operate automatically; which shall make use of the city water pressure or other source of water pressure to assist in the operation of the mechanism; which shall take hot water from a storage tank and force it by a preponderance of pressure derived from the boiler into a receiver arranged above the boiler and in open communication therewith and from which the feed water flows into the boiler by gravity.

A particularly valuable feature of my invention resides in the ease with which my system can be designed to meet any given conditions of city water pressure and boiler pressure.

An important part of my system is a multiple cylinder trap or pump, all of the cylinders being arranged to receive steam at boiler pressure above the pistons, and to receive either city water or hot water from the storage tank below the pistons. In the present instance I have shown three cylinders, two of which receive hot water from the storage tank and one receives water at city pressure, thus when steam from the boiler is admitted to the three cylinders the pressure on the three pistons is opposed only by the city water pressure on one piston and by boiler pressure on the other two, and as the boiler pressure is much higher than the water pressure there is a preponderance of pressure to force the hot water from the two cylinders into the receiver which is open to the boiler.

While my improved method of feeding boilers is in effect a uniform feed, it is not continuous but is distinguished from the usual continuous feed produced by the use of steam pumps and the like, by the fact that the feed water is projected into the receiver in successive measured quantities, the projection of the successive quantities being separated by suitable intervals of time suf-

ficient to permit the reestablishment of the boiler pressure in the receiver and the flow, by gravity after such equalization of pressure of the water from the receiver into the boiler. While each quantity or batch of water is being discharged into the receiver, it of course condenses the steam in the receiver thereby becoming heated to practically boiler temperature. For this reason a boiler fed with water by this system is not subject to contraction and expansion strains as is usual where the feed water is colder than the boiler temperature. Consequently the boiler is longer lived and requires less repairs. Furthermore although the condensation of the steam in the receiver reduces the pressure therein, still as the receiver is in constant communication with the steam space of the boiler the steam immediately flows into the receiver thereby quickly restoring the boiler pressure in the receiver and permitting the heated feed water to flow into the boiler before the pressure is again reduced in the receiver by the next entering batch or quantity of water.

When my system is understood it will be clear that any preponderance of pressure to force the hot water into the boiler can be arranged for by providing more or less cylinders and varying the proportion of cylinders receiving city water and hot water from the tank to meet the conditions presented.

My invention consists in the improvements in boiler feed systems as above outlined and as hereinafter more fully explained in conjunction with the accompanying drawings and as particularly pointed out in the appended claims.

In said drawings:

Fig. 1, is a side elevation of a steam boiler equipped with a feed water system embodying my invention in one form;

Fig. 2, is a rear end elevation of the boiler and equipment;

Fig. 3, is a fragmentary, side elevation of the multiple cylinder pump or trap;

Fig. 4, is a horizontal section on the line 4—4 of Fig. 3;

Fig. 5, is an end view of the pump as seen from the right hand end of Fig. 3;

Fig. 6, is a top plan view of the pump;

Figs. 7 and 8 are fragmentary, horizontal, sectional views on the lines 7-7 and 8-8 respectively of Fig. 5;

5 Fig. 9, is a vertical, central section of the pump on the line 9-9 of Fig. 6;

Fig. 10, is a vertical, longitudinal section on the line 10-10 of Fig. 6;

10 Fig. 11, is a fragmentary, vertical, central section of the upper end of the receiver on the line 11-11 of Fig. 2; and

Fig. 12, is a horizontal section on the line 12-12 of Fig. 11.

15 In said drawings 1 represents a horizontal cylindrical steam boiler having a steam dome 2 near its forward end and a large feed and blow off pipe 3 at its rear end.

20 In my system of water feed I provide a tank 4 open at its top to the atmosphere and preferably arranged at a higher level than the boiler in which water to feed the boiler with is maintained at a suitable level by any of the usual means for this purpose, such as a float valve, not shown, which would 25 control the entrance of water from a suitable supply, such as a city water main 6. I also provide a receiver 5 which is preferably in the form of a vertical cylindrical tank set at a higher level than the boiler. This receiver 30 is connected directly to the steam space of the boiler by a pipe 7 which connects the top of the boiler with the top of the receiver and is controlled by a hand valve 8.

35 The bottom of the receiver is connected to the inlet pipe 3 by a feed pipe 9 of ample area which is controlled by a check valve 10 near the receiver, a check valve 11 near the inlet pipe and a hand valve 12 between the check valve 11 and the inlet pipe 3, and as the receiver is at a higher level than the boiler and its upper end is in open communication 40 with the steam space of the boiler, any water delivered into the receiver flows at once by gravity into the boiler. A drain pipe 13 is also provided for the receiver controlled by a hand valve 13'.

45 The water in the tank 4 is heated by any suitable means, preferably by the return drip from the heating system and the condensate from the steam using devices such as engines, etc. Of course, the water can be heated by steam direct from the boiler if necessary. It is preferable to maintain the water in the tank 4 at about 212 degrees. To take the hot water 50 from the tank 4 and force it into the receiver is the object and aim of the apparatus now to be described.

55 For this purpose and in the present instance I have provided a multicylinder pump 14 having three vertically arranged parallel cylinders 15, 16 and 17. The cylinder 16 is arranged between the other two. Each cylinder contains a piston head 18 which is movable up and down therein and each piston head is connected by a piston rod 19 project-

ing through the upper head 20 of the cylinders and suitable stuffing boxes 21 with a cross head member 22. The several pistons move up and down as a unit. The upper ends of the several cylinders are connected to the steam supply pipe 23 which leads from the steam dome 2. This pipe 23 is controlled by a hand valve 23' and feeds into a manifold pipe 24 which has branches entering each cylinder.

70 A horizontal pipe 25 connects the manifold 24 with the supply pipe 23. This pipe 25 is controlled by a valve 26 provided with a valve stem 27 projecting through a suitable stuffing box 28 and by which the valve is opened by lifting or pulling up the stem. Beyond the connection to the manifold the pipe 25 is provided with another valve 29 which is also adapted to be opened by lifting or pulling out its valve stem 30. The valve 29, as shown, is of the balanced type but might be of the same form as the valve 26 if desired.

75 The operating arrangement is such that these two valves are alternately opened and closed. The valve 26 is the steam supply valve and the valve 29 is the steam exhaust valve. When one is open the other is closed. When the supply valve 26 is open steam enters the upper ends of all the cylinders above 80 the pistons therein and applies pressure on the several pistons to force them down. When the supply valve 26 is closed and the exhaust valve 29 opened the steam is permitted to escape from the several cylinders and the pressure is taken off of the pistons.

85 The lower ends of the two outer cylinders 15 and 17 are connected by a pipe 31 with the hot water tank 4 near or at its bottom. This pipe is controlled by a hand valve 32 and a check valve 33 between cylinder 17 and the tank 4. The check valve 33 opens towards the cylinder and closes towards the tank 4. The pipe 31 branches to each of said cylinders 15 and 17 and leads on to the upper end of the receiver 5. A check valve 31' is interposed in the pipe 31 between the pump and the receiver 5. This check valve opens towards the receiver and closes towards the pump. The pipe 31 is also controlled by a hand valve 34 located near the receiver.

90 The lower end of the middle cylinder 16 is connected to a supply of water under pressure by a pipe 35 which is controlled by a hand valve 36. This pipe 35 extends beyond the pump and connects with the boiler inlet pipe 3, and is controlled between the pump and the inlet pipe by a hand valve 37 and a check valve 37'.

95 The delivery pipe 31 enters the center of the upper head of the receiver and is provided with a distributor 39 on its end within the upper end of the receiver. This distributor is in the form of a hollow ball provided with four delivery holes arranged around its 100

horizontal circumference and the holes are adapted to deliver the water into the upper part of the receiver in several streams which are projected against the sides of the receiver 5 and are broken up into small drops. This assists in the rapid absorption of heat by the water from the high pressure and high temperature steam contained in the receiver.

The pipe 9 connecting the bottom of the 10 receiver to the water inlet of the boiler is cross connected by a pipe 40 with the hot water tank 4 for a purpose to be explained. This connection is controlled by a hand valve 41. This pipe 40 is also connected to the steam 15 line 25 for the pump by a pipe 42, but beyond a check valve 43 and is adapted to direct the exhaust steam from the pump into the hot water tank 4. A drain pipe 44 is provided connected to the pipe 42 and controlled by 20 a hand valve 45.

For controlling the operation of the pump the following valve operating mechanism is provided. The stems 27 and 30 of the two steam control valves 26 and 29 are connected 25 to a rocking lever 46 at points 47 and 48 respectively and on opposite sides of the pivotal mounting 49 of the lever 46. The pivotal mounting 49 is carried on the top of a standard 50 which is mounted at its lower 30 end in a threaded opening 51 in a bushing 52 in turn mounted in a T forming part of the steam line 25. By this means the pivotal mounting is made easily adjustable vertically to adjust the operation of the valves 26 35 and 27 to make them close properly.

The lever 46, as shown in Fig. 1, extends to the left and is provided with a counterweight 53 on its end which tends to tip the left hand end of the lever down, thus closing the exhaust valve 29 and opening the steam valve 26. To minimize the drop of the weight there is a spring rest 54 provided arranged on top of the drain pipe 44 and which cushions the impact of the weight when it drops.

For tipping the lever 46 in the opposite direction to close the steam valve 26 and open the exhaust valve 29 there is provided an arm 55 secured rigidly on the cross-head 22 and projecting out to the right beyond the cross-head. As best shown in Figs. 5 and 6, the projecting end of the arm 55 is divided into two parts 56 and 57. The part 56 projects toward the front and the part 57 toward the rear. The function of the part 56 is to contact with the right hand end 58 of the tipping lever 46 as it approaches the downward limit of its movement and force that end of the lever 46 down, thus closing the steam valve 26 and opening the exhaust valve 29.

For retaining the lever 46 in this position until the cross-head has risen to the upper limit of its movement, there is a latch lever 59 provided which is in the form of a bell-crank pivotally mounted at 60 on the upper end of a standard 61 mounted at its lower end on a

projection 62 rising from the cylinder head casting 20. This standard 61, as shown in Fig. 8, is slidably mounted in the projection 62 so as to be capable of being adjusted vertically and is held in its adjusted position by a set screw 63. One arm 64 of the bell-crank depends below the pivotal mounting 60 and the other arm 65 projects horizontally toward the rear. This horizontal arm carries an adjustable weight 66 for causing the lever to tip in one direction and the lever is tipped in the opposite direction by the arm 57 of the valve operating arm 55. This arm 57 as it approaches the upper limit of its movement contacts with the arm 65 and lifts it swinging 70 the other arm 64 of the bell-crank 59 to the right, see Fig. 7. The arm 64 of the bell-crank has a notch 67 providing a shoulder 68 arranged to project over the right hand end 75 of the lever 46 and retain this lever in position with its right hand end depressed, the steam valve 26 closed and the exhaust valve 29 open. The weight 66 tips down the arm 65 of the bell-crank and swings the arm 59 to the left, Fig. 7, as soon as the end 58 of 80 the lever 46 is forced down by the arm 56 far enough to enter the notch 67 below the shoulder 68. The parts are retained in these positions until the cross-head rises and the arm 57 lifts the arm 65 of the bell-crank, thus 85 releasing the lever 46 from the shoulder 68 and permitting the weight 53 to tip the lever 46 in the other direction, thus opening the steam valve 26 and closing the exhaust valve 29.

A stop 69 is provided for preventing the arm 64 swinging out too far to the left.

There is a pipe 70 connecting the water supply pipe 35 with the hot water tank 4 for a purpose to be described, and this pipe is 90 controlled by a hand valve 71. There is also a connection between the water supply and the pipe 31; this consists of the pipe 73 connected at one end to the water supply and controlled by the hand valve 72 and the other end 95 of which is open and controlled by a drain valve 74; this is for a purpose to be described.

The operation of the pump is as follows: assuming that the device is operating to feed hot water to the boiler through the receiver.

The hand operated valves are in the following condition:

Valve 36 is open to allow water under pressure to enter the lower end of the middle cylinder from the water main; valve 32 is 100 open to allow hot water from tank 4 to enter the two outer cylinders; valve 23' is open to supply steam from the boiler to the pump; valve 34 is open to allow the hot water to be forced from the two outer cylinders into the 105 top of the receiver; valve 8 is open to supply live steam to the receiver; valve 12 is open to permit the hot water in the receiver to flow into the boiler; valve 41 is closed to shut off connection between the receiver and the tank 110

4; valve 71 is closed to shut off communication between the hot water tank and the middle cylinder; valves 72 and 74 are closed.

It will be understood that during normal operation of the device the lower end of the middle cylinder is continuously in communication with the city water main, and that the pressure operates to push the several pistons up when it is permitted to and is forced back into the main when the steam pressure is applied to the several cylinders.

Assuming that the parts are in the positions shown in Fig. 1; steam enters the manifold 24 through the steam valve 26 and forces the several pistons down. As the pistons descend the hot water which has filled the two outer cylinders through the pipe 31 is forced out of the cylinders and up into the receiver and the city water in the middle cylinder is forced back into the main. When the pistons reach their lowermost positions where they rest upon supporting bars 75 in the bottoms of the cylinders and which bars prevent the pistons closing the outlets from the cylinders, the lever 46 has been reversed by the arm 56 and is latched in its reversed position. Thus holding the steam valve 26 closed and the exhaust valve 29 open. This permits the water pressure below the middle piston to lift the several pistons and the cross-head to their upper positions, thus again filling the outer cylinders with hot water from the tank 4 and completing a cycle of operations.

The direct connection 40 between the receiver and the hot water tank is for assisting in heating the tank when starting the system into operation, the condensed steam in the receiver being forced over into the tank to assist in heating the water therein. In case of emergency the hot water can be forced directly into the boiler instead of into the receiver; this is done by closing the valves 34 and 36 and opening the valves 71 and 37. Under these circumstances the middle cylinder only receives hot water and the two outer cylinders are in communication with the city main. The operation is similar to the instance already described except that we have more power to lift the pistons and more pressure to force the water into the boiler.

A thermometer 9' is provided on the pipe 9 for indicating the temperature of the feed water. In use the water in the tank 4 is usually maintained at about 212 degrees temperature and the water is delivered from the receiver to the boiler at 300 degrees or more. There is no difficulty experienced in pumping hot water and all of the heat units in the steam are conserved.

A drain pipe 76 is provided connected to all of the cylinders near their upper ends and is controlled by a hand valve 77. This is to drain off the condensed steam when warming up the pump.

It is to be noted that the several pistons of

the pump work up and down together, that is, in unison and not alternately, that the water is forced into the receiver by the downward stroke of the pistons, that no water is delivered during the upward stroke of the pistons and that consequently the water is fed into the receiver in measured quantities or batches and that these are separated as to time by the interval necessary for the pistons to accomplish their upward movement.

This feature of the separation of the quantities of water fed into the receiver is of the utmost importance.

The projection of the water into the receiver in the manner described and particularly by the use of the distributor 39 in the top of the receiver or some similarly acting device, causes a sudden absorption by the incoming water of heat from the steam in the receiver, the heating of the feed water to nearly boiler temperature, and the consequent reduction of the pressure in the receiver to a point below boiler pressure.

As the connection of the receiver with the lower part of the boiler is controlled by the check valve 10, the water cannot back up from the boiler, and as the top of the receiver is open to the steam space of the boiler, the pressure in the receiver is promptly equalized with that in the boiler, the steam flowing into the receiver through the pipe 7.

As soon as the pressure in the receiver is equalized with that in the boiler, the water in the receiver flows into the boiler by gravity through the pipe 9. The time required to equalize the pressure in the receiver with that in the boiler is allowed for by the regulation of the speed of the pump, so that sufficient time is allowed to permit one quantity of the delivered water to flow out of the receiver into the boiler before the next quantity is forced into the receiver.

It is also to be noted that there is no moving mechanism in the receiver or between the pump and the boiler, that there are no traps or other devices to be taken care of and that it is not necessary to vent or relieve any trap or space and that consequently all heat units in the steam are conserved and that none are lost or thrown away.

It will now be clear that for a specific installation it is only necessary to proportion the pump and the receiver to the maximum quantity of feed water required so that the water cannot be fed to the receiver faster than it can flow into the boiler and that to feed it slower than the maximum it is only necessary to reduce the speed of the pump.

The system is highly economical and efficient and on ordinary sized plants of about 100 horse-power the saving over other methods is from one-fourth to one-third of the fuel.

As many modifications of my invention will readily suggest themselves to one skilled

in the art, I do not limit or confine my invention to the specified details of construction or operation herein shown and described.

I claim:

5. 1. The improvement herein described comprising a boiler feed system, including a multi-cylinder pump, pistons in the several cylinders connected for similar simultaneous movement, connections between the like ends 10 of each cylinder and the boiler to be fed, to receive steam therefrom, the opposite end of at least one cylinder connected with a supply of water under pressure less than the normal boiler pressure, the opposite ends of 15 at least two of the cylinders connected to a supply of hot water and to the boiler, automatically operable means for controlling the inlet and exhaust of the steam to the cylinders.
- 20 2. In a boiler feed system, a pump having a plurality of double acting cylinders, pistons in the several cylinders, the pistons all connected to a single cross-head to act as a unit, one end of one cylinder connected to 25 a source of supply of fluid under pressure of less than normal boiler pressure, the similar ends of the other cylinders connected to a source of supply of feed water, and also to the boiler to feed same, the opposite ends 30 of the several cylinders connected to a source of steam pressure, and automatically operable valve means for controlling the operation of the pump.
- 35 3. In a system of the kind described, a boiler, a multi-cylinder pump, a hot water tank, a receiver connected to the boiler to receive steam therefrom and having a second connection with the boiler for feeding water thereto, connection between the boiler 40 and the similar ends of the several cylinders to supply steam to the cylinders, the opposite end of at least one of the cylinders connected to a source of supply of fluid under a pressure less than the normal steam 45 pressure in the boiler, the remaining opposite ends of the cylinders having an aggregate area greater than the one connected to the source of fluid pressure and connected to the hot water tank to receive hot water therefrom and to the receiver to deliver the hot 50 water thereto.
4. In a boiler feed system of the kind described, a source of supply of hot water, a double acting pump cylinder connected at one end to a water pressure pipe, and connected at the other end to the boiler to receive steam under pressure therefrom, other cylinders likewise connected at one end to the boiler to receive steam pressure therefrom, and at their other ends to a source of supply of hot water and to the boiler and automatically operable valve means for controlling the operation of the pump, the several pistons of the several cylinders being 60 connected together to act as a unit and 65 adapted to deliver predetermined quantities of water separated by predetermined intervals of time.
5. A boiler feed pump comprising a plurality of double acting cylinders, pistons in the cylinders connected to reciprocate in unison, means for alternately delivering steam pressure from the boiler to similar ends of the several cylinders and exhausting the steam therefrom, the opposite end of at least 70 one cylinder adapted to be continuously connected to a source of fluid pressure less than the normal pressure in the boiler, means for alternately connecting the opposite ends of the remaining cylinders to a source of 75 supply of feed water and to the boiler, the arrangement being such that when steam is applied to the like ends of the several cylinders, the aggregate pressure is more than the aggregate pressure at the opposite ends 80 of the cylinders.
- In testimony whereof, I have hereunto set my hand, this 15th day of September, 1927.
